ELECTRIC SWITCH

Robert L. Brady and Alexander C. Wall, Indianapolis, Ind., assignors to P. R. Mallory & Co., Inc., Indianapolis, Ind., a corporation of Delaware

Application February 9, 1945, Serial No. 577,062

8 Claims. (Cl. 200—5)

1

This invention relates to heating controls, and has particular reference to electric switching devices and their arrangements and operation.

An object of this invention is to provide improved means and method of electric switching.

Further objects will be apparent from the following specification and claims, and the accompanying drawings.

In the drawings:

Figure 1 is a perspective view of an electric range with electric switches thereon in an illustrative embodiment of this invention;

Figure 2 is an enlargement in front elevation of a switch as in Figure 1;

Figure 3 is a diagram of one operative circuit for use with a switch of this invention;

Figure 4 is a side elevation of the switch of Figure 1;

Figure 5 is a face view of the back of the switch of Figure 1;

Figure 6 is an exploded view of the switch of Figure 1, in perspective and partial section;

Figure 7 is face view of the back of the indexing drum of the switch of Figure 1;

Figure 8 is a perspective view of the indexing spring member of the switch of Figure 1;

Figure 9 is an elevation of a contact arm of the switch of Figure 1; and

Figure 10 is a perspective of a resilient contact arm and support of the switch of Figure 1, having contacts for opposing those of the structure of Figure 9.

The particular switch and arrangement shown and described herein is merely in illustration of this invention. While this switch is particularly useful on electric ranges it may also be used with other heating units. Electric furnaces are cited as one example. Many variations of the particular disclosure given herein may be made without departing from the spirit and scope of the invention.

A particular feature of this invention is the effectively linear movement to progressively increase heat, and the reverse to decrease heat. This is accomplished through a series of progressive heating steps, preferably included in an arc of less than 180° and approximately 120°. This arrangement makes possible major improvements in heating unit designs. An important usefulness is provided in that adjustment may be easily accomplished by a thrusting movement, without the necessity of grasping the switch control arm. Operation is simple, more convenient than previous structures, and easy for unskilled operators.

Another feature is the provision of a choice of a considerable variety of heats. This makes for very flexible operation of a heating unit. In this illustration a choice of eight heats is given. More or fewer may be provided as desired. On initial operation, it is simple to throw the switch tem-

porarily to maximum heat position for a warm-up period, and then adjust to the heat desired. These settings may be made through continuous, effectively straight line movements.

A further feature is the simplicity, effectiveness and low-cost design of the mechanical-electrical construction and arrangement of the switch. Preferably, a double pole double throw type switch mechanism is used, with an operating lever pivoted so that up movement progressively increases heat, and down movement decreases heat through the same heat positions. The "off" position is preferably at the top. The movement could, however, readily be from side to side or at an angle, if desired. The construction is such that several parts are in duplicate, and many less parts are used in comparison with previous heating unit switches. Cost is accordingly considerably reduced.

As in Figure 1, switches of this invention are mounted in locations 1 on an electric range 2, instead of the usual rotary type switches. One switch is preferably provided for each heating unit, although a plurality of units may be controlled by one switch if desired. The heating units may comprise one or more elements, and the power supply may be at one or more voltages. Such variation may entail fewer or more heat positions.

The preferred structure provides each heating unit with two elements of different heating capacity with the power supplied through a three wire 115-230 volt line.

The following table illustrates the heat progression as the switch is moved through its series of heat positions. As an arbitrary and illustrative choice element A is rated at 100 watts at 115 volts and element B is rated at 150 watts at 115 volts.

Heat positions	Element A			Element B		Total watts
	Volts	Watts		Volts	Watts	
1	0	0	Off	0	0	0
2	230	400	High	230	600	1,000
3	115	100	-----	230	600	700
4	0	0	-----	230	600	600
5	230	400	Med.	115	150	550
6	230	400	-----	0	0	400
7	115	100	-----	115	150	250
8	0	0	-----	115	150	150
9	115	100	Low	0	0	100

In accordance with the circuit of Figure 3, the two heating elements are shown as resistances A and B. By opening and closing the contacts C, D, E, F, and G, the various combinations of voltages and elements are utilized to produce the progressive heating steps. These contacts are opened and closed through the mechanical operation of the switch.

Referring to the heat position table above, the following table illustrates the contact action.

Heat position	Contacts—blank spaces indicate contacts open				
	C	D	E	F	G
1	Closed			Closed	Closed
2	do	Closed			Do.
3			Closed		Do.
4	do			Closed	
5	do			Do.	
6	do				
7	do		Closed		
8	do		Closed	Do.	
9	do	Closed			

As in Figure 6, the switch comprises three main assemblies, the base and contact assembly 3, the housing assembly 4, and the rotor drum cam assembly 5.

The base and contact assembly is also somewhat shown in associated Figures 2, 3, 4, 5, 9 and 10. The base 6 is formed of Bakelite or other suitable insulating material and has the various contact members mounted thereon. At one end of the base 6 the 230 volt contact support 7 is mounted, and at the other end of the base 6 the 115 volt contact support 8 is mounted. Both of these supports have the form shown in Figure 9 with uprights 9 and 10 and contacts 11 and 12. Through contact support 7 either of the heater unit elements A or B may be connected to the 230 volt line, and, similarly, A or B may be connected to 115 volt line through contact support 8.

The lead to heater unit A is through flexible contact arm 13 and its support 14, and the lead to heater unit B is through flexible contact arm 15 and its support 16. Figure 10 illustrates these assemblies, with flexible arm 17 welded to the support 18. The arm 17 is provided with contacts 19 for cooperation with (Figure 9) contacts 12, and with rounded stand-out portions 20. These rounded portions 20 ride on cam surfaces 21 of the rotor drum 22 of assembly 5.

Without the drum assembly 5 in the switch assembly, the flexible arms 13 and 15 keep contacts D, E, F and G closed. The normal situation, however, when drum assembly 5 is in the switch assembly, is for contacts D, E, F, and G to be open as so forced by engagement of the cam surfaces 21 of the drum 22 with the rounded portions 20. As drum 22 is rotated in the operation of the switch, the rounded portions 20 are dropped into recesses 23 and contacts D, E, F or G are selectively closed in accordance with the calculated positioning of the recesses 23.

The off and on switch comprises normally separated contact arms 24 and 25. Arm 24 is connected to the common lead of the three wire power supply and arm 25 is connected to both heater elements A and B.

The housing assembly 4 comprises a metal cover 26 to fit over the contact base 6, and a resilient indexing arm 27 secured to the cover 26 by lugs 28 and 29. Cover 26 is provided with lugs 30 to fit in corresponding slots 31 in base 6. Lugs 30 and slots 31 may be formed as to shape or dimension so that the cover 26 may only be assembled in one positional relation to base 6. Indexing arm 27 is formed of one piece and has upwardly bent portions 32 for engaging the drum 22. The rough H form of arm 27 with cross-piece 33 at one end, provides a member of extra resilience and strength.

The drum assembly 5 comprises the drum 22 of Bakelite or other suitable insulating material,

and an operating arm 34 with insulation knob 35 mounted thereon and knurled as at 36 to provide a better grip. Drum 22 is recessed at each end to form cam rims 24 and hubs 37. The drum 22 is mounted in the switch assembly by passing a shaft through the hubs 37 and openings 38 in cover 26. Hubs 37 may be varied as to form or dimension to assure proper assembly relation with the switch assembly.

10 While the end surfaces 21 of the drum 22 provide cam surfaces for operating contacts D, E, F, and G, the outer side wall is provided with indexing V grooves 39 for engagement with bent up portions 32 of indexing spring 27. A central un-grooved portion 40 holds contact C, arms 24 and 25, closed in all switch positions except the "off" position. A single groove 41 permits arm 25 to spring away from arm 24 and cut off power from the entire switch.

15 What is claimed is:

1. An electric switch comprising a base having an on and off contact pair, and two sets of selector units, each unit comprising two pairs of cooperable contacts and each unit including a support arm with a resilient contact arm mounted on said support arm and a cam rider portion on said contact arm on opposing sides of said support arm; a housing mounted on said base; and a drum cam mounted in said housing for movement into operating relation with said on and off contact pair and said cam rider portions.

2. An electric switch comprising in combination a generally cylindrical actuating member mounted for rotation, a cam surface on each end face of said member, a cam surface on the circumferential face of said member, at least one cam follower element biased against each of said cam surfaces, a system of electric contacts for each cam follower element operable by displacement of said element, and means for rotating said actuating member thereby to actuate said systems of contacts in predetermined sequence.

3. An electric switch comprising in combination a rotatable actuating member, a pair of contact springs bearing displaceable contacts at each end thereof spacedly mounted in their mid-portion across the end faces of said member, a cam surface on each end face of said member, a cam rider for each end of said springs cooperating with the respective cam surface to displace the corresponding contact, a relatively fixed contact for each displaceable contact to control an electric circuit therewith, means for rotating said actuating member thereby to cause actuation of said contacts in predetermined combination and sequence, and indexing means for said member to positively define successive positions of said member with respect to portions of said cam surfaces.

4. In an electric switch, a base, a control member having a cylindrical face rotatably mounted on said base, means for defining successive angular positions for said control member including transversely grooved portions at the respective opposite sides of said cylindrical face and spring members secured to said base for engaging said grooved portions, a control lever fixed to said control member and extending through said face, said lever being adapted to move said control member to any of said angular positions, contacts mounted on said base, a cylindrical cam surface at the central portion of said face for operating said contacts, a cam surface extending along one edge of said cylindrical face, and a set of contacts operated by said edge cam surface.

5. In an electric switch, a base, a control member having an arcuate face rotatably mounted on said base, means for defining successive angular positions for said control member including transversely grooved portions at the respective opposite sides of said arcuate face and spring members secured to said base for engaging said grooved portions, a set of contacts mounted on said base, an arcuate cam surface at the central portion of said face for operating said contacts, cam surfaces extending along the respective edges of said face, and contact means operated by said edge cam surfaces, said contact means including a pair of spaced contact springs of resilient material, means for supporting each of said springs at the central portion thereof, cam follower surfaces at the respective intermediate portions of each spring which are adapted for engagement with the respective edge cam surfaces on said control member, and contact sets at the respective ends of each spring, each set comprising a movable contact at the end of the spring and a fixed contact, said contacts being urged into closed position by the resiliency of said material, each edge cam surface comprising raised portions for displacing the adjacent spring member to thereby open the associated set of contacts and depressed portions for permitting said adjacent spring to return to its normal position and thereby close said associated set of contacts.

6. An electric switch comprising a pair of spaced contact springs formed from resilient material, means for supporting each of said springs, a cam follower surface on each of said springs, and a contact set at the end of each spring, each set comprising a movable contact at the end of the spring and a fixed contact, said contacts being urged into closed position by the resiliency of said material, a drum type cam rotatably mounted between said springs and having a plurality of cam surfaces which are adapted to engage the respective cam follower surfaces on said springs, each cam surface comprising raised portions for displacing the adjacent spring member to thereby open the associated set of contacts and depressed portions for permitting said adjacent spring to return to its normal position and thereby close said associated set of contacts.

7. An electric switch comprising a pair of spaced contact springs formed from resilient material, means for supporting each of said springs

at the central portion thereof, cam follower surfaces at the respective intermediate portions of each spring, and contact sets at the respective ends of each spring, each set comprising a movable contact at the end of the spring and a fixed contact, said contacts being urged into closed position by the resiliency of said material, a drum type cam rotatably mounted between said springs and having a plurality of cam surfaces which are adapted to engage the respective cam follower surfaces on said springs, each cam surface comprising raised portions for displacing the adjacent spring member to thereby open the associated set of contacts and depressed portions for permitting said adjacent spring to return to its normal position and thereby close said associated set of contacts.

8. An electric switch comprising a plurality of spaced contact springs formed from resilient material, means for supporting each of said springs, a cam follower surface on each of said springs, and a contact set associated with each of said springs, each set comprising a movable contact mounted on the spring and a fixed contact, said contacts being urged into closed position by the resiliency of said material, a cam rotatably mounted between said springs and having a plurality of cam surfaces which are adapted to engage the respective cam follower surfaces on said springs, each cam surface comprising raised portions for displacing the adjacent spring member to thereby open the associated set of contacts and depressed portions for permitting said adjacent spring to return to its normal position and thereby close said associated set of contacts.
